UNITED STATES PATENT OFFICE.

PAUL R. BARUFKE, OF WEST HOBOKEN, NEW JERSEY.

CORN AND CALLUS CUTTER AND TRIMMER.

1,359,315.

Specification of Letters Patent. Patented Nov. 16, 1920.

Application filed October 10, 1917. Serial No. 195,819.

To all whom it may concern:

Be it known that I, PAUL R. BARUFKE, a citizen of the United States, residing at West Hoboken, in the county of Hudson and State of New Jersey, have invented certain new and useful Improvements in Corn and Callus Cutters and Trimmers, of which the following is a specification.

This invention relates to an improved device for cutting corns and callus places and the principal object of the invention is to provide an instrument of the character described so constructed that one jaw or plate can be set upon the foot with the corn or callus place protruding through an opening formed in the plate and the second jaw or plate then moved across the first plate to bring the cutting edge of the second jaw into operative engagement with the corn and thus cut the corn or callus place away.

Another object of the invention is to so construct this instrument that the cutting edge of the second plate will move across the opening of the first plate in the proper manner for efficient cutting.

Another object of the invention is to provide an instrument of the character described which will be simple in construction and efficient in operation and to further so construct it that it may be easily sharpened.

This invention is illustrated in the accompanying drawings, wherein:

Figure 1 is a plan view looking at one side of the instrument,
Fig. 2 is a view similar to Fig. 1 looking at the opposite side of the instrument, the instrument in this view being closed instead of open as shown in Fig. 1, and
Fig. 3 is a sectional view taken along the line 3—3 of Fig. 2.

In the drawings wherein for the purpose of illustration is shown a preferred embodiment of my invention, the numeral 10 designates a lower blade and 11 designates an upper blade, both of which are heart-shaped and in the present instance are of substantially the same size. The jaws are pivoted together in overlapping relation by a bolt 12 or the like, adjacent their inner ends, and each blade is provided with a handle 13 extending longitudinally of the axis of the blade whereby the upper blade may be swung across the lower blade. A substantially elliptical opening 14 is provided in the lower

blade adjacent the forward or pointed end thereof and extends transversely of the longitudinal axis of the blade. A second opening 15 is provided in the lower blade and is arranged adjacent the inner end thereof. The inner edge 16 of this opening forms an acute angle with the longitudinal axis of the blade 10 and accordingly the opening 15 is adapted for cutting callus places while the opening 14 is particularly adapted for cutting corns. The outer edges 17 of both openings are beveled or slightly rounded inwardly to abut with or catch on the part to be cut. The relative inner convex cutting edges 18 of the heart-shaped plates are provided with cutting edges, the blade 10 having a rounded cutting edge, and it will be manifest that these two cutting edges may intersect and be effectively used in severing cuticles.

From the foregoing, it will be apparent that when the blade 10 is placed upon a foot so that the opening 14 encircles a corn and the edge 17 abuts therewith and the handles 13 move together, the cutting edge 18 of the blade 11 will move forwardly and outwardly of the opening 14 toward the far end thereof. Also this cutting edge will move forwardly and outwardly toward the edge 17 of the opening 15 and in both instances, successive portions of the cutting edge will successively engage and establish a shearing action through the corn or callus patch and will not gouge through the part to be severed.

What is claimed is:

1. A surgical instrument including a pair of pivotally connected blades having their coacting cutting edges convexed to present a maximum angle therebetween at any relative position of the blades.
2. A surgical instrument including a blade having a plurality of irregularly shaped openings of different configurations, and a second blade movable relative to the first and having a cutting edge adapted to intersect the edges of the openings.
3. A surgical instrument comprising a pair of blades pivotally connected together at points adjacent the rear ends thereof and having convex edges, the convex edge of one blade being provided with a cutting edge, the co-acting blade being provided with a pair of openings, one of which is

arranged transversely of the longitudinal axis of the blade adjacent the forward end thereof, and the other opening defining an acute angle with the longitudinal axis of the blade and arranged adjacent the rear end of said blade.

In testimony whereof I affix my signature in presence of two witnesses.

PAUL R. BARUFKE.
